UNITED STATES PATENT OFFICE.

EMIL JOHN ENS, OF NEWARK, NEW JERSEY.

TALLY-STRIP FEED MECHANISM.

Application filed March 5, 1926. Serial No. 92,527.

This invention relates to tally strip feed mechanism for adding, listing, calculating, combined typewriting and adding machines, and other machines of similar general character, wherein it may be desirable to obtain a record or duplicate of items listed or added on a regular work sheet.

The object of the present invention is to provide a simple, inexpensive and durable tally strip feed mechanism which may be attached to the machine with which it is to be employed, by the utilization of a single post or support and will be adapted to automatically feed the tally strip to effectuate the purposes of the tally strip feed mechanism of the application of Frederick W. Bernau, Serial No. 60,861, filed October 6, 1925.

The present improvement dispenses with the feed roll and pressure roll of the aforesaid Bernau mechanism, obviates the necessity of providing a double post support for a device of this character, reduces the number of parts required and otherwise changes the construction without sacrifice of efficiency and enables the mechanism to be used at points on machines of the character previously set forth where it is not always easy to install a supplemental mechanism such as is embraced in a tally strip feeder.

The present invention provides for feeding a tally strip in such manner that the items printed on the work sheet will also be printed on the tally strip, without the tally strip being carried by the platen and without requiring the use of a carbon sheet or strip, thereby enabling the platen and the work sheet to be moved from column to column without disturbing the tally strip and also, permitting the insertion or removal of work sheets around the platen entirely independently of the tally strip.

As my invention provides for mounting the tally strip independently of the platen and of the work sheet and for the automatic feeding of the tally strip, for a given listing of items on the tally strip and work sheet, the section of the tally strip on which said items are listed may be detached at any time, without interfering with the work sheet and thus a given list can be attached to a group of checks or vouchers, for instance, immediately on the completion of listing and totalling them on the machine on which the device is used.

In carrying out my invention I provide an improved pusher or feeder adapted to be automatically moved one space at the completion of each operation of the adding or other machine on which the work is being performed, whereby the tally strip is automatically fed step by step on successive operations of the machine.

The invention also contemplates the provision of improved means for holding the tally strip to prevent it from slipping, either when it is stationary or when it is being fed by the pusher. Additional to the aforesaid means is means for disabling the tally strip feeder so that it will be inoperative when the use of the tally strip is not desired.

As with the mechanism of the Bernau invention of Serial No. 60,861, so with the present invention, I use as a tally strip a thin, transparent, suitably prepared paper which is disposed between the printing ribbon and the printing type. When the types strike to print the item on the work sheet which is carried by the platen, the tally strip is forced by said type against the ribbon and thus receives an impression which is a duplicate of that made through the ribbon on the work sheet and, thus, the necessity for providing a carbon sheet in order to obtain an impression on the tally strip is obviated. The tally strip being transparent the impression can be read through it from its front side.

To illustrate how my invention may be applied to the adding machine which lists or prints I have shown in the drawings and described hereinafter so much of the "Ellis" listing adding machine as will afford a clear understanding of the use of the invention and the manner in which the feeding mechanism is automatically operated by the mechanism of the adding machine. I wish it to be understood, however, that my improvements may be applied to other adding machines which print items and I do not, therefore, limit the use of the invention to the "Ellis" machine.

I am aware that modifications may be resorted to without departing from the principle of the invention and, except where specified in the claims, I do not limit the invention to the specific embodiment shown in the drawings and hereinafter described.

In the accompanying drawings:

Figure 1 is a part side elevation and part

vertical section showing my tally strip feed mechanism applied to an "Ellis" adding listing machine;

Figure 2 is a detail vertical section through the tally strip feed mechanism, the operating connections also being shown; dotted lines representing the movement of the parts;

Figure 3 is a detail elevation of the tally strip feed mechanism;

Figures 4, 5, and 6 are sectional detail views, respectively on lines 4-4, 5-5, 6-6, Figure 3, taken through the paper table, illustrating the action of the paper feeder or pusher; and

Figure 7 is a detail view of the paper holder.

The case of the "Ellis" listing adding machine is designated B⁴⁸ and only the upper part thereof is shown. The settable keys of the usual key board are not shown. The platen appears at S, being movably mounted in a laterally travelling carriage.

In the present instance I propose to utilize the movement of the paper feed lever P⁷⁴ for the automatic operation of the feeding mechanism for the tally strip.

The printing group is designated P⁵⁴ and the inked ribbon, fed by any ribbon mechanism, appears at R. The paper table is shown at T and the work sheet appears at A in position around the platen S on the table T.

Reference may be had to the patent to 35 Halcomb Ellis No. 1,197,276, September 5, 1916, combined adding machine and typewriter, for a further disclosure of the printing group P⁵⁴, the paper feed lever P⁷⁴, and other mechanisms of the "Ellis" machine and 40 further explanation thereof, is therefore, omitted.

A suitable paper roll holder 1 is attached to the case B⁴⁸ and contains a roll of thin, transparent paper which serves as the tally strip 2. The tally strip is guided horizontally from its roll and then upwardly in front of the ribbon R by a sheet metal paper guide 3 whose forward part is detachably connected to the ribbon fork 50^P by a 50 pin 4.

The tally strip feeding mechanism embodying my present invention is carried by a frame comprising a bracket or upwardly extending arm 5 which has a paper table 6 for the feed of the tally strip 2 thereacross. To detachably fasten the arm 5 to the top of the case B⁴⁸, a post 7 is fastened to said case by a suitable nut and has a slot in which the lower edge of the arm 5 is stepped, a 60 guide-hole slot 8 being provided in the arm 5 to receive a fastening screw 9. This construction enables the device to be mounted on the case B⁴⁸ by the use of a single post, in such manner that the tally strip feed 65 mechanism may be removed, or attached, as

desired. Furthermore, as the device requires but a single post for its attachment it can be readily applied to any machine of the class set forth at the desired point, without interfering with other mechanisms or devices thereof.

My improvements entirely dispense with the use of feed and pressure rolls, the purpose of the invention being to feed the tally strip 2 by an improved pusher or feeder 75 which appears at 10. This feeder or pusher is pivotally or swingingly mounted on a pin 11 one of whose ends is slidably mounted in a slot 12 in an ear 13 which forms a part of the paper table 6. The remaining end 80 of the pin 11 is secured to the ear 14 of the actuator or slide 15. The pusher 10 is maintained in contact with the tally strip 2 by a spring 16 which is coiled around the pin 11 and engaged with the pusher 10. The other 85 end of the spring 16 presses against the paper holder 17.

The paper holder 17 has ears which are carried by a pin 18 whose ends are mounted in the ear 13 and arm 5. The paper holder 90 17 has fingers 17' which bear on the tally strip 2 and are normally held against it by a spring 19 whose ends are coiled about the pin 18 and bear against the edge of the paper table 6. The fingers of the paper 95 holder 17 are spaced apart to enable the pusher 10 to play up and down between them. The pusher 10 has lugs 20 which are adapted to slide under the lugs 21 on the 100 ends of the fingers of the paper holder when the pusher rises to feed the tally strip 2. When the pusher returns to its normal position, the lugs 20 slide up and over the lugs 21 and the pusher then falls back to its 105 normal position. The arrangement is such that 105 when the pusher 10 advances to feed the tally strip, the lugs 20 on said pusher engage the insides of the lugs 21 on the paper 110 holder and "cam" the paper holding fingers upwardly so that they are out of contact with the tally strip 2 and hence do not interfere with the free feeding of the tally strip by the pusher 10. Immediately the pusher 10 has moved to a position where the lugs 20 are clear of the lugs 21, on the feeding 115 movement of the pusher, the disengagement of the lugs 20 from the lugs 21 permits the spring 19 to snap the paper holder back into engagement with the tally strip. This occurs before the pusher 10 has started its 120 receding movement. Consequently, the tally strip 2 is held, after feeding, and cannot accidentally slip.

The actuator or slide 15 serves as the means for moving the pusher 10 to feed the 125 tally strip 2. This slide has slots 22 through which pass headed studs 23, such arrangement constituting a guide for the actuator 15. A spring 24 connected to one of the studs and to the stud 25 on the actuator 15, 130

normally retracts the actuator and the pusher.

When use of the tally strip is not required the actuator 15 may be latched in a raised, 5 inoperative, position by a latch 26 which is pivoted at 27 and has a tooth 28 adapted to project through an opening 29 in the arm 5 and to engage with the upper end of the actuator 15.

10 The paper table 6 is provided with a slot 30 through which the tally strip 2 passes and there is a paper cutter or knife 31 which enables the tally strip to be torn off.

When the machine is operated, the paper feed lever P^{74} having first moved downwardly, to assume the full line position shown in Figures 1 and 2, thereafter rises, forcing up the push link 32 which is provided for the purpose of operating the tally strip feed 20 mechanism. The push link 32 elevates the actuator 15, whereupon the pusher 10 is lifted, then feeding the tally strip 2. As the pusher 10 advances, its lugs 20 contact with the lugs 21 and raise the paper holding fingers free of the tally strip but immediately the lugs 20 pass beyond the lugs 21, the paper holder is released, and the fingers are then instantly reengaged with the strip 2 due to the action of the spring 19. When 30 the paper feed lever P^{74} turns to normal position, the actuator 15 is drawn downwardly by its spring, whereupon the lugs 20 ride on the lugs 21 until the pusher finally resumes its normal position.

35 During the advance movement of the pusher 10 when the lugs 20 are under the lugs 21 of the paper holder, not only is the paper holder released from the tally strip by a "camming" action so that there will be 40 no interference with the feeding of the tally strip, but also, the paper holder then places a pressure on the pusher 10, causing the latter to firmly engage the tally strip, thus insuring positive feeding of the said strip.

45 When the tally strip is not needed, the actuator 15 may be latched in its raised position.

As the checks or vouchers or items are listed, the printing group P^{54} forces the tally strip 2 against the ribbon R and the ribbon R against the work sheet A which is 50 around the platen S. The blow delivered not only causes printing through the ribbon R on the work sheet A but also printing 55 on the tally sheet or strip 2 without resorting to the use of a carbon strip or sheet. The carriage and the platen can be moved or spaced to any desired tabulated position so that listing of the items on any part or in 60 any column of the work sheet may be had. This in no manner interferes with the tally strip 2 as the latter is not around the platen but is independent thereof. As the tally strip is in line with the printing group P^{54} , 65 so long as said strip is used, it will receive

a duplicate impression of each item printed on the work sheet A.

When the listing of any group or series of vouchers, checks, etc. is completed, it is unnecessary to await the completion of the entire listing as the tally sheet or strip can be torn off by pulling it across the knife 31, thus enabling the listing on the tally strip for that particular group of checks or vouchers to be at once associated with the 75 group.

What I claim is:

1. In a tally strip feed mechanism, the combination with a pusher tally strip feeder, and means for actuating said feeder, of 80 means for holding the paper.

2. In a tally strip feed mechanism, the combination with a pusher tally strip feeder, and means for actuating said feeder of 85 means for holding the paper, said feeder being arranged to automatically release the tally strip holding means when said feeder is feeding the tally strip.

3. In a tally strip feed mechanism, the combination with a spring actuated holder 90 normally adapted to bear on the tally strip to retain it in position, of a reciprocatory tally strip feeder having means adapted to "cam" the tally strip holder out of engagement with the tally strip when said feeder is 95 feeding the tally strip, and means for shifting the tally strip feeder.

4. In a tally strip feed mechanism, the combination with a tally strip table over 100 which the tally strip passes, of a spring pressed tally strip holder having fingers which normally bear on the tally strip, a reciprocable, pivoted or swingingly mounted tally strip pusher or feeder which has means adapted to engage with the aforesaid fingers 105 on the feeding movement of said feeder to "cam" said holder out of engagement with the tally strip, said means being adapted to ride on the aforesaid fingers on the retrograde movement of the pusher or feeder, and 110 means for operating said feeder.

5. In a tally strip feed mechanism, the combination with a table over which the tally strip travels, said table having an ear, and an arm connected to the table and serving 115 as a support for the entire mechanism, of a rockably mounted, spring actuated, tally strip holder carried by the table, an actuator slidably mounted on said arm, a pin carried by said actuator and also slidably mounted on the ear aforesaid, and a spring actuated pusher or feeder which is pivoted on the pin and is adapted to engage the paper holder when said pusher advances to feed the tally strip, whereby the holder 120 is thereby released from the tally strip while also exerting pressure on the pusher to hold it against the tally strip, said pusher being adapted to become freed from the holder after the tally strip has been fed. 125 130

6. In a tally strip feed mechanism, the combination with a spring actuated tally strip holder normally engaged with the tally strip, of a pusher feeder for the tally strip, and actuating means therefor, said pusher feeder cooperating with the paper holder when said feeder is advanced to feed the paper, whereby the holder exerts pressure on the pusher feeder during the feeding 10 operation and the holder is released from the tally strip while the strip is being fed.

7. In a tally strip feed mechanism, the combination with means for holding the tally strip, of means for feeding said strip, said feeding means releasing the holding means on the forward or feeding stroke, and said holding means releasing the feeding means on the return stroke of the feeding means.

In testimony whereof I affix my signature.

EMIL J. ENS.
